The ornamental design for a tote for a slow cooker, as shown and described.

DESCRIPTION

FIG. 1 is a three quarter top, front, side perspective view of a tote for a slow cooker showing my new design;

FIG. 2 is a right side elevational view thereof, taken in the direction of arrow 2 in FIG. 8;

FIG. 3 is a left side elevational view thereof, taken in the direction of arrow 3 in FIG. 8;

FIG. 4 is a front elevational view thereof, taken in the direction of arrow 4 in FIG. 8;

FIG. 5 is a rear elevational view thereof, taken in the direction of arrow 5 in FIG. 8;

FIG. 6 is a top plan view thereof, taken in the direction of arrow 6 in FIG. 8;

FIG. 7 is a bottom plan view thereof, taken in the direction of arrow 7 in FIG. 8; and,

FIG. 8 is a view identical to FIG. 1 with descriptive legend directional arrows included which are necessary for better understanding of the drawing in accordance with 37 CFR 1084(o) and appropriate with good engineering practices, so as to best indicate in what directions previous views are taken so that nothing regarding the design sought to be patented is ambiguous or left to conjecture.

Any portion of any figure shown in broken lines are for illustrating stitching; and

Any portion of any figure shown in phantom lines are for environmental purposes only and form no part of the claimed design.
